UNITED STATES PATENT OFFICE.

JOSEPH MANDEL AND JAMES P. HENDERSON, OF LOGANSPORT, INDIANA,
ASSIGNORS TO THE NATIONAL METALLIC POCKET FASTENER COMPANY,
OF SAME PLACE.

STAPLE INSERTING AND CLINCHING MACHINE.

SPECIFICATION forming part of Letters Patent No. 512,383, dated January 9, 1894.

Application filed July 6, 1893. Serial No. 479,750. (No model.)

To all whom it may concern:

Be it known that we, JOSEPH MANDEL and JAMES P. HENDERSON, citizens of the United States, residing at Logansport, in the county 5 of Cass and State of Indiana, have invented certain new and useful Improvements in Machines for Inserting and Clinching Staples; and we do hereby declare the following to be a full, clear, and exact description of the invention, such as will enable others skilled in the art to which it appertains to make and use the same.

Our invention relates generally to machines for inserting and clinching staples, and particularly to a machine for inserting metallic staples or fasteners through one or more thicknesses of cloth, paper, felt, or like material, and for clinching the legs of the staples around reinforcing plates held in position on 10 the under surfaces of the materials operated upon, and through holes in the ends of which plates the legs of the staples pass, which will hereinafter be fully described, and particularly pointed out in the claims.

Our invention, while it may be used for other purposes, is especially designed to provide means for reinforcing the corners of the pockets of coats, trousers, and other wearing apparel, where they are subjected to strain, 15 in such a manner as to greatly cheapen the sewing up of such garments, while providing a more certain preventative from tearing than is provided by the present means used. In place of the present laborious stitching which 20 has to be resorted to to prevent such tearing, we propose to substitute a simple mechanical fastening, which can be inserted by a single operation of our machine around a suitable reinforcing plate, which is held by the operation 25 of our machine in position, on the under surface of the material to be acted upon, for the legs of the staple to pass through holes in its ends. Clinching means are provided for turning the protruding legs of the 30 staple up under the plate and for securely clinching them there. The fastening thus afforded is much more secure than that at present used, and is also much more durable.

Our invention is an improvement on the 35 form of staple inserting and clinching ma-

chine shown and described in United States Letters Patent No. 389,661, granted to us on September 18, 1888, and has for its object to reduce to a single movement, caused by the depression of a single foot lever, the number 55 of movements necessary to hold in position the staple, and the reinforcing plate, to insert the staple through the holes in the plate, to clinch the legs of the staple around the plate, and to place a new staple and a new plate in 60 operative position, instead of having to perform these operations separately, as was necessary in the use of the machine referred to.

Our invention consists, therefore:—First. In improvements in the staple holding and 65 feeding device, whereby staples, held upon a suitable former, are one by one automatically forced into position to be engaged by the staple inserting mechanism, and inserted into the cloth, or other material operated on. We 70 provide means for interrupting the forward feed of the staples while the staple inserting mechanism is operating, in order that a second staple may not crowd into position in the path of the same while it is forcing one staple into 75 position. The mechanism for effecting this end is operated by the descent of the staple inserting mechanism. Second. In improvements in the staple inserting mechanism, whereby the movement of the same is simplified, and its operation made certain and 80 complete. The staple inserting plunger is so connected with the staple feeding device that it automatically cuts off and allows the feeding of the staples into position in the staple 85 guide block in which the said plunger reciprocates. Third. In improvements in the plate holding and feeding device, whereby the successive placing of the plates into operative position over the central aperture 90 formed in the machine bed is automatically accomplished by means operated by the action of the staple inserting mechanism. Fourth. In improvements of the clinching mechanism, whereby the same may be actuated by a further movement of the same 95 mechanism which operates the staple inserting mechanism. In our machine the clinching mechanism is situated in the central aperture, formed in the machine bed. Fifth. 100

In improvements in the operative mechanism, whereby the various portions of the staple inserting and clinching mechanism are successively caused to perform their functions in due order, and without danger of confusion in operations, by mechanism operating by the depression of a single foot lever.

Our invention is fully represented in the drawings accompanying and forming a part of this application, in which the same reference numerals refer to the same or corresponding parts, and in which—

Figure 1 is a perspective view of the top portion of our machine, the operative mechanism, and the parts immediately brought into operation thereby being hid by the top of the table. Fig. 2 is a side view of the machine partially in section, showing the various parts in operative position, and ready to be actuated to insert a staple into the piece of cloth laid on the bed plate of the machine. Fig. 3 is a similar view, the parts being shown in the position they assume when the staple has been inserted, but before the clinching mechanism has begun to act. Fig. 4 is a similar view, the clinching mechanism being shown as just having completed its operation, and before it has resumed its normal position. Figs. 5, 6, and 7 are detail views of the head of the staple feeding mechanism, and the staple plunger operating in connection therewith. Fig. 5 shows the parts in the position they assume before the staple inserting plunger has begun to act, the sliding gates which interrupt the delivery of the staples being shown open. Fig. 6 is a similar view, the parts however being shown in the position they assume when the staple inserting plunger has just completed the operation of inserting a staple. The sliding gates before mentioned are here closed. In both of these figures the outer, removable portion of the staple guide block is removed, in order to show the interior parts. Fig. 7 is a section of Figs. 2, 3, or 4, taken on the line $\times$ $\times$ and looking in the direction of the arrow. It is a rear view of the staple guide block, and shows particularly the means adapted to normally hold the sliding gates open. Figs. 8, 9, and 10 are views of the clinching mechanism, the views respectively showing the staple inserted and ready to be clinched; the legs of the staple turned in in readiness for the final clinching; and the staple finally clinched. The metal plate which holds the blades performing the clinching operation in position on the machine, and which also forms one side of the central aperture, is here removed, in order that the position of the said blades during the entire operation may be readily ascertained. The hammer actuating the clinching mechanism is here shown in section. Fig. 11 is a view of the inner surface of the outer, removable portion of the staple guide block. Fig. 12 is a view of one of the curved blades which perform the clinching operation. Fig. 13 is a view of the locking device em-

ployed in the staple holder. Fig. 14 is a view of one of the sliding gates used to interrupt the delivery of the staples. Fig. 15, shown 70 on Sheet 1, is a view of the staple, and the reinforcing plate.

Before proceeding with a description of our machine, it is well to thoroughly understand the formation of the staple, and the reinforcing plate upon which the machine operates. These are described in United States Letters Patent No. 389,660, granted to us September 18, 1888, and as there described the reinforcing plate consists of a piece of metal, formed with 80 holes in its ends for the reception of the legs of the staple, and formed with a central, longitudinal slot for receiving the clinched legs of said staple. It is intended that the legs of the staple, when clinched, shall just meet in 85 the central slot, without overlapping, so that the under surface of the goods will be smooth. It is thus necessary to use staples having different lengths when operating upon different thicknesses of cloth, in order that the legs may 90 not overlap.

Proceeding now with the description of our machine, and referring to the accompanying drawings, 1 represents the table upon which our machine is placed.

2 represents the main or central casting, which forms the bed of the machine. This casting is shown in perspective in Fig. 1, but its shape is more clearly indicated in Figs. 2, 3, and 4. Broadening at its rear end, which 95 is at the back of the table, so as to secure a firm base by which it can be securely attached to the table, it rises particularly at the front, central portion of its rear end until the desired height is attained, and then extends 100 forward horizontally, constituting the bed proper of the machine. At the front end of the casting two side arms branch out in the form of a T, and to these arms are attached the brackets 4, which thus firmly support the 105 front end of the casting at the desired height. To this broadened front end, and at a distance a little greater than the width of the legs of a staple, is secured, by means hereinafter to be described, the plate 5, which thus 110 forms in effect an extension of the machine bed. The aperture thus formed between the bed 2 and the plate 5 is called the central aperture, as it is over this aperture that the reinforcing plate is held when ready to be operated upon; it is in this aperture that the 115 legs of the staple pass, when they have been inserted through the cloth being operated upon; and it is in this aperture that the clinching mechanism is located. On the top 120 of the machine bed is fastened the bed plate 6, in the front end of which, and directly over the central aperture, is formed an opening 7 which is of just the size of a reinforcing plate, except on its front edge, where it is hollowed 125 out for a purpose hereinafter to be stated. This opening holds the reinforcing plate directly in position over the central aperture formed in the bed plate. To the machine bed 130

are pivoted the staple holding and feeding device, which has in connection therewith a staple guide block, normally held above the central aperture by its connection with the 5 staple inserting mechanism, but whose pivotal movement is such that when the staple holder is depressed, the opening in the same registers with the central aperture directly over the place where the reinforcing plate is held; the staple inserting mechanism, with the staple inserting plunger connected therewith, and also connected to the staple guide block; the plate feeding mechanism, operated by a lug formed on the rocking arm which 10 constitutes the operative means for reciprocating the staple inserting plunger in the staple guide, and the hammer which operates the clinching mechanism. The blades performing the clinching operation are also pivoted in the central aperture.

The operative mechanisms of our machine may be divided into the staple holding and feeding device; the staple inserting mechanism; the plate holding and feeding device; 25 the clinching mechanism; and the operative mechanism by which all the separate mechanisms are actuated.

For convenience of description, and in order that the construction and operation of 30 the various parts may be grasped in detail, and thus thoroughly comprehended, the various portions of the entire machine will be described separately in the order mentioned, allusion being made from time to time to the 35 other parts in order to clearly keep in mind the timing of the various movements, which enables all of the different mechanisms to operate to accomplish a single end. After such 40 separate descriptions, the entire operation of the machine will be described, and the timing of the various parts clearly ascertained.

I. The staple holding and feeding mechanism.—Between two lugs 8, projecting upward from the machine bed 2 at the extreme rear 45 end of the horizontal portion of the same, is pivoted the staple holding and feeding device 10, which consists of a staple holder 11; a tube 13, located immediately in the rear of and connected to the same, in which is located 50 the feeding device, and a staple guide block 30, which is placed at the front end of the staple holder. The proportions of the parts are such that when the staple guide block is at the lower stage of its pivotal movement, the staple guiding recess formed in the 55 same registers with the central aperture, over which the reinforcing plate is held. The staple holder consists of the U-shaped trough 11, which is of sufficient size to permit the insertion therein of the staple carrier 12, upon which the staples are arranged, and also to permit the free forward passage of said staples, as they are pushed forward by the staple feeding device, which is located in the 60 tube 13. The staple carriers 12 are pieces of wood, paper, or other suitable material, so formed that the staples will fit snugly

over them, and of length sufficient to hold the desired charge of staples for the machine. We usually charge the machine, when about 70 to operate the same, with a gross of staples, and a gross of plates, as it is convenient to put up the staples and plates in charges of that number, but the charge can of course be varied by changing the proportions of the 75 machine. In the bottom of each carrier is formed a groove 12', into which the studs 14, which project centrally from the bottom of the trough 11, enter, and thus hold the carrier in position in the said trough, and prevent it from getting twisted or turned to one side. The ends of each carrier are inclined on its bottom surface, so that by pressing on one end, the other end will be raised out of the U-shaped trough, and can be more easily 80 grasped for removal from the staple holder. By thus making the carriers removable, the recharging of the machine, when the supply of staples becomes exhausted, is made easy. The carrier is held in position lengthwise in 90 the staple holder by two U-shaped lugs, 15 and 15', which project from the bottom of the trough 11. These lugs, as the staple carrier, are shaped to fit the inner surface of the staple. The forward lug 15 is in effect merely 95 an extension of the staple carrier. The said lug extends from the extreme edge of the staple holder to a point a little behind the head 31, which forms a portion of the staple guide block. The rear lug, 15', is only of sufficient 100 length to make it firm and secure. In the tube 13, which is attached to the staple carrier immediately at its rear, is located the spiral spring 16, which acts, through the mediation of the plunger 17, to constantly force 105 the staples forward. The plunger consists of a strip of metal of the width of the U-shaped trough, which is formed at one end with a downwardly projecting lug or ear 18, which is inserted behind the U-shaped lug 110 15', and against which the spring 16 directly bears, and at the other end with downwardly turned side flanges, which extend to the bottom of the trough 11. By so forming the head of the plunger, a constant and uniform pressure against the staples is secured throughout 115 the entire travel of the plunger, as its length is sufficient to enable it to feed the last staple from the staple holder. On the top of the plunger is the rib 20, to the front end of which 120 is attached the trigger 21, by means of which the plunger may be drawn back. To the downwardly projecting lug 18 is attached the rod 22, which extends through the tube 13 sufficiently far to cause the lug 22', formed on 125 its rear end, to pass through the opening 13' formed in the end of the tube 13, when the plunger is pushed backward as far as possible. The spring 22', attached to and pressing on the rear end of the rod 22, will 13 then cause said lug 22' to engage with the side of the aperture 13', and thus permanently lock the plunger in its withdrawn position. It may be released by pressing up-

ward, and out of engagement with the side of the opening 13', the said lug 22'. The holder is provided with a removable cover 25, the forward end of which enters a recess formed in the back of the head 31, a lug 25' limiting its forward movement. It is locked in position on the holder by the pivoted pawl 23, pivoted to the top of the tube 13, which when properly turned engages with the rear end of said cover. When it is desired to insert a loaded carrier into the staple holder, the pivoted pawl 23 is turned so as to permit of the removal of the cover, the plunger 17 is withdrawn until it is locked on its rear position, and the old former is taken out. After a new carrier has been inserted, the cover is again placed in position, and then the plunger 17 is released. It is important that the cover be put on the holder before the plunger is released, as it acts to prevent the staples from rising out of position, and thus interrupting the forward feed of the staples. On the front end of the staple holder is formed the staple guide block 30, which is formed in two portions of the head 31, and the removable piece 38. The head 31 is nearly square in form. On its upper surface are formed two projections for the reception of the pivotal bolts for the levers 33. Its lower surface is somewhat inclined so that when the guide block rests against the bed plate 6, the said head may fit perfectly even on the same. On its front surface, which is perfectly smooth, and which is flush with the extreme end of the staple holder, around which the head is indeed formed, and on a plane at right angles to the length of the staple holder, are cut guide ways for the sliding gates 32, whose outer surfaces are thus flush with the surface of the head 31. One of these sliding gates is shown in detail in Fig. 14. It is a rectangle of metal, having an oval slot cut in its outer end, and having the inner surface of its rear end, as well as of its sides, beveled. It has two positions. In its outer, normal position, it is, as shown in Fig. 5, drawn outward until the inner end of the same is clear of the passage way through which the staples pass. In its closed position, each gate acts to close up one side of this passage way, thus preventing another staple from being forced out of the holder. The beveled edge permits this cutting off to be performed with great ease and accuracy. The sliding gates are actuated by means of the levers 33, acting through the pins 34, which pass through the oval slots formed in the gates as before mentioned. The levers 33 are pivoted to the upper portion of the head 31, and extend above said head, so that when the upper ends of the said levers are forced outward, the lower ends are forced inward, thereby closing the sliding gates 32, and shutting off the supply of staples. The oval form of the apertures in the sliding gates permits the radial inward movement of the pins 34, while allowing the gates to reciprocate back and forth in a straight line. The gates are normally held

open by the U-shaped spring 35, shown in Fig. 7. The lower portion of this spring is fastened to the bottom of the staple holder, 70 as shown, and the side arms of the same, projecting upward, engage with lugs 33', which project from the back surfaces of the levers 33 below the pivotal point of the same, and thus press the lower arms of said levers outward. The range of movement necessary to close the sliding gates is not great, and can be varied by proper adjustment of the relative lengths of the arms of the levers 33. 75

II. *The staple inserting mechanism.*—The staple inserting mechanism consists of a plunger, which reciprocates in the staple guide 30, and a rocking arm for actuating the same, which is pivoted to the bed of the machine, and to which the plunger is connected by a link connection. The plunger 40 is a piece of metal of the width of a staple, and at its sides of the thickness of a staple. Centrally and longitudinally of the same is formed the slot or groove 41, around which the plunger 90 is thickened, as shown in the drawings, in order to enable it to withstand the strain to which it is subjected at this point. The plunger is connected to the upper side of the staple guide block by means of a pin 42, which 95 passes through the piece 38 into the head 31, in such a manner that when the plunger is in its upper position, as shown in Fig. 5, the lower end of the said plunger is just above the passage way through which the staples 100 pass into the staple guide way. The plunger is normally held in this position by the spring 39, which, attached to the upper surface of the staple holder head, presses against the lower side of the end of the rocking arm 45, 105 and maintains a constant distance between the staple holder and the said rocking arm. When, however, the staple plunger is caused to descend, it moves from this position through the extreme range of its movement 110 into the position shown in Fig. 6, with its lower end flush with the bottom of the staple guide block 30, forcing downward by such movement the staple which is in its path, and inserting the same into the fabric. The slot 41 115 is of sufficient length to allow this movement. The removable piece 38, as shown in Fig. 11, is cut away so as to fit the peculiar shape of the plunger, and to afford the same a secure guide. The rocking arm 45, to which the 120 plunger 40 is connected by a suitable link connection 44, is of the shape shown in the drawings, and is pivoted between lugs 47, rising at the extreme base of the bed 2 of the machine. A portion of it extends downward 125 below the surface of the table 1, passing through an aperture in the machine base, and is operated by the operative mechanism in such a manner as to cause the arm to rock upon its axis, and the upper portion of the 130 same to move forward and downward, carrying the staple plunger down to the central aperture in the machine bed. The link connection of the plunger with the rocking arm

permits the up and down movement of the plunger, while the rocking arm moves forward and downward. On the lower surface of the front end of the rocking arm, and on each side of the same, is secured a strip of metal 46, the forward end of which is pointed. The connection between the rocking arm and the staple holder is such that the upper ends of the levers 33 rest against the arm just in front of the said strips. When, therefore, the rocking arm is depressed, and moves forward and downward, the upper ends of the levers ride on the inclined ends of the strips 46 until the level portion of the same is reached, and then during the further movement of the rocking arm slide along the level portions of the strips without any further outward movement. The outward movement of the upper ends of the levers 33 causes an inward movement of the lower parts of the same, and thus closes the sliding gates 32. The upper portion of the rocking arm 45 is normally held raised by the spring 51, which, attached to the rear, perpendicular portion of the machine bed 2, presses against the same. If the pivotal support of the staple holder be borne in mind, and also the fact that it is held elevated from the machine bed by being connected with the rocking arm 45, it will be seen that during the first part of the movement of said rocking arm, the staple holder is forced downward, the said holder turning upon its pivot until the staple guide block strikes the bed plate 6. When the end of the movement is reached, the staple plunger descends, and forces the staple into the cloth. It is during the first part of the movement of the rocking arm, while the staple holder is turning on its pivot, that the sliding gates 32 are closed. Thus the gates are closed, and the outward passage of the remaining staples prevented before the staple plunger has begun to descend, and the said sliding gates are not opened until the staple plunger is completely raised. There is therefore no opportunity for the staples to get turned or twisted out of their position in the staple guide block. During the reciprocation of the plunger, its smooth rear face slides against the smooth inner face of the staple guide block. The staples are held in position in the staple guide block, after they have been forced into the same by the feed plunger, by friction. The rocking arm 45 is formed at its rear with an opening 48, through which the tube 13 passes. The opening is so shaped as to permit the radial movement of said tube during the operation of the machine. The said rocking arm is also formed with a lug 50 on one side of the same, at a point just above its pivot. This lug performs a function in operating the plate feeding mechanism which will hereinafter be noted.

III. *The plate holding and feeding device.*—

The plate holding and feeding device consists of a holder for the plates, and means for successively forcing each plate into position over

the central aperture. The plate holder is a tube 55, shaped so as to receive the plates, to the bottom of which is connected the tube 60, which contains a coiled spring designed to operate the pressure plunger 57, which acts to force the plates upward. The plates are held, previously to being placed on their holder, upon a strip of paper, or other suitable material, a single charge for the machine, say a gross, being threaded upon each strip. The holder 55 is provided with a removable cover 56, which extends the whole length of the same, and the bottom end of which is provided with a curved or bent projection, which enters into a slot in the top of the tube 60, and thus partly holds the cover on the tube. A U-shaped piece 58, which slides over the cover, completes the locking of the same to the holder. The plunger 57 is provided at its lower end with a handle 57', by means of which the plunger can be drawn down to the bottom of the plate holder 55, and then, by turning the handle into a slot formed in the tube 60, permanently locked in its withdrawn position. When it is desired to charge the plate holder, the plunger 57 is withdrawn, the cover 56 of the holder removed, and the plates placed in the holder. The cover is now locked in position, and the paper upon which the plates were threaded is withdrawn. To place the plate holder in position on the machine, its upper end is inserted through an opening in the table, and pushed upward through an opening in the machine bed, which is fitted to receive it, until the stop 61 gives warning that the extreme upward movement has been reached. The upper end of the holder is then flush with the top of the machine bed. A pawl 62, pivoted to the bottom of the machine bed, is now turned until one of its arms presses against the holder, and holds it in place by frictional pressure. Lengthwise of the plate 6 and of the width of a reinforcing plate is cut a slot 63, which is covered, with the exception of its extreme front end, by a metal plate 64, whose under surface is thickened directly over the slot 63 so as to make the difference between the bottom of the plate 6 and that of the plate 64 equal to the thickness of one reinforcing plate. The extreme front portion of this slot, which is rounded, has been given the designation 7, and its purpose has been stated as holding the plate in position over the central aperture. The formation of the front of this aperture, as shown in Fig. 1, enables the plates to be picked out of the same when desired without difficulty. When the plate 6 is in position on the bed of the machine, the slot 63 is over the horizontal portion of said bed. Upon the top of the bed, and guided by the walls of said slot, reciprocates the plate feed plunger 65, whose width is that of the slot, and whose thickness is that of a reinforcing plate, or such as to cause its top surface to fit snugly against the bottom surface of the plate 64. The plunger is attached at

its rear end to the metal piece 66, which extends across the machine bed, and is situated in a recess or depression in the same, so that its upper surface is level with the machine bed. This piece is connected at one side by means of the rod 67 to the upper end of the lever 68, which is pivoted to the side of the machine bed. The lower, curved end of this lever rests against the lug 50 formed on the rocking arm 45 in such a manner that when the said rocking arm is depressed, the lever 68 will be caused to turn on its pivot, and draw back the metal piece 66, and thereby the plunger 65. The recess formed in the machine bed in which the said piece 66 rests permits of such backward movement. When the plunger is in its normal position, it is forward with its front end nearly on a line with the central aperture, but when the plunger is withdrawn through the depression of the rocking arm, and parts acting in connection therewith, its front end is drawn back to a position just behind the end of the plate holder. If now the plunger 57 be allowed to press against the plates, it will force the top plate against the surface of the reciprocating feed plunger 65. When this is withdrawn, either through the action of the rocking arm, or by drawing back the connecting rod 67 by hand, the top plate will be forced up against the lower surface of the plate 64. Only one reinforcing plate can be thus forced up, however, because of the thickness of the plate 64. When the feed plunger now moves forward, it will carry with it this plate, and will force it into position over the central aperture, in position to have the proper action take place thereon. Bearing in mind the operation of the rocking arm, it will be observed that when the same is being depressed, and thus causing the operation of the staple inserting mechanism, the plunger 65 is withdrawn, and a new plate forced into position to be carried forward by said plunger, and thus to replace the plate just used. When the rocking arm rises, the said plate is forced into its operative position. The feeding forward of the plate thus takes place at the same time that the feeding of the staple takes place. The formation and arrangement of the parts herein described are such as to prevent two plates being fed forward at the same time, or any confusion of the feeding of the staples to arise.

IV. *The clinching mechanism.*—The clinching mechanism consists of two curved blades, situated in the central aperture, which normally hang with their upper ends apart, but which are so operated by the hammer actuating the same that the upper ends are brought together, thus bending the legs of a staple together, and then the entire blades are given an upward movement, which performs the final clinching. The front end of the machine bed 2 is chiseled away to permit the insertion of the metal pieces 71, which project downward below the machine bed.

The outer face of the same is level with the front of the machine bed. On these projecting pieces 71 are formed the supporting pins 69, on which are hung the curved blades 70. These curved blades perform the clinching of the staple. One of them is shown in detail in Fig. 12. As there shown the blade consists of an upper portion 73, substantially rectangular in form, from which depend the curved wings 73'. In the blade is formed an oblong slot 74, through which the supporting pin 69 passes. The blade is thickened around this slot, as it is here subjected to the greatest strain, the plate 5, which holds these blades in position, being cut away accordingly. On the upper edge of the blade, and on the inner side of the same is formed a projecting lug 75, which of itself in great part performs the clinching operation. The surfaces 76 and 77 of the blade are somewhat inclined, for a purpose which will hereinafter appear. The blades hang, in their normal position, with their upper ends separated, and with the curved wings 73' quite close together. The distance between the two projecting lugs 75 is a little greater than the distance between the legs of the staples. In the operation of the machine, these projecting lugs are brought together, and then the entire blades are forced upward, the oblong slot through which the supporting arms pass permitting such movement, and the upper surfaces of the blades which are now on a line with, and just a little below the surface of the machine bed 2, together with the lugs 75, act to positively and effectually clinch the legs of the staple into the cloth, and around the reinforcing plate. The purpose of inclining the surfaces 76 and 77 is now apparent. It is so that the said surfaces may be level with the machine bed at the proper instant of time. These blades are operated by means of a hammer 80, which is pivoted to a lug projecting from the bottom, rear surface of the machine bed 2. This hammer is in effect a bell crank lever, whose short arm extends under the table, and is operated upon by the operative mechanism, and whose long arm extends forward to operate the clinching blades. We designate this long arm, however, as the hammer, as it in reality performs the hammering requisite to clinch the staples. In an aperture in the hammer 80, through the rear portion of which the plate holder 55 passes, and through which the curved wings 73' pass, is formed the V-shaped lug 81, which occupies the space between the curved wings mentioned. The operation of the hammer is clearly apparent from Figs. 8, 9, and 10. When the hammer is raised, the V-shaped lug 81 forces apart the lower ends of the curved blades, causing the lugs 75 to approach each other, and thus bend inward the legs of the staples. When the upper surface of the hammer reaches the surface 77 of the blades, it forces the entire blades upward, and thus causes the final clinching. When the hammer is lowered, the weight of the

same causes the blades 70 to separate, and the curved wings to draw together, as the whole weight of the hammer is sustained by the said wings.

5 V. *The operative mechanism.*—The operative mechanism for the machine is a bell crank lever 90, which is hung upon a shaft 91, journaled on the lower side of the table in suitable supports, and which is actuated by a 10 crank arm 93, which in turn is operated by the arm 94, pivotally attached to it, and which is connected at its lower end to an ordinary foot treadle. A spring 96 normally holds the bell crank lever 90 in the position shown in 15 Fig. 2. By the depression of the treadle, the lever is caused to rotate, one arm 90' of the same striking the lower curved portion of the rocking arm 45. This portion of the rocking arm is curved so as to make the movement 20 of the upper part of the same more uniform. The rocking arm is thus depressed until it has reached the lowest phase of its movement. By this time the portion 90' of the lever 90 has completed its possible movement upon 25 said rocking arm. The arm 90' of the lever 90 now strikes the lower projecting portion of the hammer 80, and causes the same to turn upon its pivot, and perform the clinching operation. The hammer does not act to 30 clinch the staple, however, until the staple has been driven home in the goods.

Operation: After the staple holder, and the plate holder have been put in position, and the pressure plungers operating upon the 35 same have been brought into action, the machine should be placed in operative position by drawing back the plate feed plunger 65, and placing a plate in position over the central aperture. The goods to be operated on 40 should then be placed in position under the staple inserting mechanism. Upon the depression of the operative treadle, the bell crank lever 90 is turned, and the arm 90' caused to strike the lower portion of the rocking arm 45. This causes the upper portion 45 of the same to be turned on its pivot, and after the staple holder has been moved so that the staple guide block is over the central aperture, with the staple guide in registering connection therewith, during which 50 movement the sliding gates have been closed, and the feeding of another staple prevented, the staple plunger is caused to descend, and the staple is forced into the goods. During 55 this operation the reciprocating plunger 65 has been drawn back, and a plate has been forced into position to be carried forward by the next forward movement of the said plunger. The apparatus is now in the position 60 shown in Fig. 3. Upon further descent of the treadle, the arm 90' of the lever 90 strikes the lower arm of the hammer 80, causing the upper portion of the same to rise, and thus separate the wings of the clinching blades, 65 thereby forcing together the legs of the inserted staple, and then causing the clinching blades to be forced upward, and the legs of

the staple to be securely clinched. The machine is now in the position shown in Fig. 4. When the treadle is raised, the hammer first 70 falls, forcing the clinching blades apart, and placing them in their normal position; and then, on further elevation of said treadle, and consequent movement of the bell crank lever, the rocking arm rises, a plate is forced into 75 position over the central aperture, and, the sliding gates in the staple holder at this point opening, another staple is forced into position to be operated upon. The machine is now in condition to repeat its former operation. 80

Having thus fully described our machine, its construction and operation, what we claim as new, and desire to secure by Letters Patent, is—

1. In a machine for inserting and clinching staples, the combination with the machine bed having a central aperture formed therein over which a plate rests on said bed, of a staple holding and feeding device having a staple guide in connection therewith, a plunger 90 adapted to reciprocate in said staple guide, a plate holding and feeding device, operating at the end of the reciprocation of said plunger to feed a plate into position over the central aperture a clinching mechanism, means 95 for causing the reciprocation of said staple plunger and the operation of the clinching mechanism, and means operating in connection with the reciprocation of said plunger for causing the automatic operation of the staple 100 and the plate feeding devices, substantially as described.

2. In a machine for inserting and clinching staples, the combination with the machine bed having a central aperture formed therein 105 over which a plate rests on said bed, of a staple holding and feeding device having a staple guide in connection therewith, a plunger adapted to reciprocate in said staple guide, a plate holding and feeding device, operating 110 at the end of the reciprocation of said plunger to feed a plate into position over the central aperture a clinching mechanism, means for causing the reciprocation of said staple plunger and the operation of the clinching 115 mechanism, means for automatically interrupting the feed of staples during the reciprocation of said plunger, and means operating in connection with said reciprocation for causing the automatic operation of the staple 120 and the plate feeding devices, substantially as described.

3. In a machine for inserting and clinching staples, the combination with the machine bed having a central aperture formed therein 125 over which a plate rests on said bed, of a pivoted staple holding and feeding device, a staple guide in connection therewith adapted to register with the central aperture, a plunger adapted to reciprocate in said staple guide, a 130 plate holding and feeding device, a clinching mechanism, means for causing the pivotal movement of the staple holder the reciprocation of the staple plunger and the operation

- of the clinching device, means for automatically interrupting the feed of staples during the reciprocation of said plunger, and means operating in connection with such reciprocation for causing the automatic operation of the staple and the plate feeding devices, substantially as described.
4. In a machine for inserting and clinching staples, the combination with the machine bed having a central aperture formed therein over which a plate rests on said bed, of a pivoted staple holding and feeding device, a staple guide in connection therewith adapted to register with the central aperture, a pivoted 75 rocking arm having attached thereto a plunger adapted to reciprocate in said staple guide, a plate holding and feeding device, a clinching mechanism, means for causing the pivotal movement of the staple holder the reciprocation of the staple plunger and the operation of the clinching mechanism, means for automatically interrupting the feed of staples during the reciprocation of said plunger, and means operating in connection with such reciprocation for causing the automatic operation of the staple and the plate feeding devices, substantially as described.
5. In a machine for inserting and clinching staples, the combination with the machine bed, having a central aperture formed therein over which a plate rests on said bed, of a pivoted staple holding and feeding device, a staple guide in connection therewith normally held above the central aperture but adapted to register with said aperture by the movement of the staple holder, a pivoted rocking arm having attached thereto a plunger adapted to reciprocate in said staple guide, a plate holding and feeding device, a clinching mechanism, means for operating the rocking arm and thereby causing the pivotal movement of the staple holder and the reciprocation of the staple plunger, the operation of the clinching mechanism, and the automatic action of the staple and plate feeding devices and means operating during the pivotal movement of the staple guide for automatically interrupting the feed of staples during the reciprocation of the staple plunger, substantially as described.
6. In a machine for inserting and clinching staples, the combination with the machine bed having a central aperture formed therein over which a plate rests on said bed, of a staple holding and feeding device having a staple guide in connection therewith, a plunger adapted to reciprocate in said staple guide, a plate holding device, a reciprocating plunger adapted to successively bring each plate into position over the central aperture, and operating at the end of the reciprocation of the staple plunger a clinching mechanism, means for reciprocating the staple plunger and for operating the clinching mechanism, and means operating in connection with the reciprocation of the staple plunger for causing the automatic feeding of a staple and a plate into position substantially as described.

7. In a machine for inserting and clinching staples, the combination with the machine bed having a central aperture formed therein over which a plate rests on said bed, of a pivoted staple holding and feeding device having a staple guide in connection therewith, a pivoted rocking arm having attached thereto a plunger adapted to reciprocate in said staple guide, a plate holding device, a reciprocating plunger adapted to successively bring each plate into position over the central aperture, a clinching mechanism, means for operating the rocking arm and thereby causing the pivotal movement of the staple holder the reciprocation of the staple plunger and the operation of the clinching mechanism, and means brought into operation by the reciprocation of the staple plunger for automatically feeding a staple and a plate into position, substantially as described.
8. In a machine for inserting and clinching staples, the combination with the machine bed having a central aperture formed therein over which a plate rests on said bed, of a pivoted staple holding and feeding device having a staple guide in connection therewith, a pivoted rocking arm having attached thereto a plunger adapted to reciprocate in the staple 95 guide, a plate holding device, a reciprocating plunger, actuated through intermediate mechanism by a lug on the rocking arm, adapted to successively bring each of the plates into position over the central aperture, a clinching mechanism, and means for operating the rocking arm and thereby causing the pivotal movement of the staple holder the reciprocation of the staple plunger, the operation of the clinching mechanism and the automatic 100 feeding of a plate and a staple into position, substantially as described.
9. In a machine for inserting and clinching staples, the combination with the machine bed having a central aperture formed therein over which a plate rests on said bed, of a staple holding and feeding device having a staple guide in connection therewith, a plunger adapted to reciprocate in said staple guide, a plate holding device, a reciprocating plunger 115 adapted to successively bring each plate into position over the central aperture, and operating at the end of the reciprocation of the staple plunger a clinching mechanism, means for causing the reciprocation of said staple plunger and the operation of the clinching mechanism, means for automatically interrupting the feed of staples during the reciprocation of said plunger, and means for operating in connection with such reciprocation for causing the automatic operation of the staples and plate feeding devices, substantially as described.
10. In a machine for inserting and clinching staples, the combination with the machine bed 130 having a central aperture formed therein over which a plate rests on said bed, of a pivoted staple holding and feeding device having a staple guide in connection therewith, a piv-

oted rocking arm having attached thereto a plunger adapted to reciprocate in said staple guide, a plate holding device, a reciprocating plunger, actuated through intermediate mechanism by a lug on the rocking arm, adapted to successively bring each plate into position over the central aperture, a clinching mechanism, means for operating the rocking arm, thereby causing the pivotal movement of the staple holder, the reciprocation of the staple plunger, the operation of the clinching mechanism and of the staple and plate feeding devices, and means for interrupting the feed of the staples during the reciprocation of the staple plunger, substantially as described.

11. In a machine for inserting and clinching staples, the combination with the machine bed having a central aperture formed therein over which a plate rests on said bed, of a pivoted staple holding and feeding device, a staple guide in connection therewith normally held above the central aperture but adapted to register with the same, a pivoted rocking arm having attached thereto a plunger adapted to reciprocate in said staple guide, a plate holding device, a reciprocating plunger, actuated through intermediate mechanism by a lug on the rocking arm, adapted to successively bring each plate into position over the central aperture, a clinching mechanism, means for operating the rocking arm and thereby causing the pivotal movement of the staple holder, the reciprocation of the staple plunger, the operation of the clinching mechanism and the automatic operation of the staple and the plate feeding devices means brought into operation during the pivotal movement of the staple guide for interrupting the feed of staples during the reciprocation of the staple plunger, substantially as described.

12. In a machine for inserting and clinching staples, the combination with the machine bed, having a central aperture formed therein over which a plate rests on said bed, of a staple holding and feeding device having a staple guide in connection therewith, a plunger adapted to reciprocate in said guide, a plate holding and feeding device, operating at the end of the reciprocation of said plunger to feed a plate into position over the central aperture a clinching mechanism situated in the central aperture, means for reciprocating the staple plunger, and for operating the clinching mechanism, and means operating in connection with the reciprocation of the staple plunger for automatically actuating the staple and the plate feeding devices, substantially as described.

13. In a machine for inserting and clinching staples, the combination with the machine bed having a central aperture formed therein over which a plate rests on said bed, of a staple holding and feeding device having a staple guide in connection therewith, a plunger adapted to reciprocate in said staple guide, a plate holding and feeding device, a clinching

mechanism situated in the central aperture, a hammer for actuating the same pivoted to the machine bed, means for causing the downward movement of the staple plunger and thereafter actuating the said hammer, and means operating in connection with the reciprocation of said plunger for automatically actuating the staple and the plate feeding devices, substantially as described.

14. In a machine for inserting and clinching staples, the combination with the machine bed having a central aperture formed therein over which a plate rests on said bed, of a staple holding and feeding device having a staple guide in connection therewith, a plate holding and feeding device, operating at the end of the reciprocation of said plunger to feed a plate into position over the central aperture a clinching mechanism situated in the central aperture, means for causing the downward movement of the staple plunger and thereafter actuating the clinching mechanism, means for automatically shutting off the supply of staples during the reciprocation of said plunger, and means operating in connection with such reciprocation for causing the automatic operation of the staple and the plate feeding devices, substantially as described.

15. In a machine for inserting and clinching staples, the combination with the machine bed having a central aperture formed therein over which a plate rests on said bed, of a staple holding and feeding device, pivoted to the machine bed, and having a staple guide in connection therewith which is normally held above said central aperture, but is adapted to register with the same, a pivoted rocking arm having attached thereto a plunger adapted to reciprocate in said staple guide, a plate holding and feeding device, a clinching mechanism situated in the aperture in the machine bed, a hammer actuating the same pivoted to the machine bed, means for depressing the rocking arm, thereby causing the pivotal movement of the staple holder the downward movement of the staple plunger, and for thereafter actuating the clinching mechanism, means, operating during the movement of the staple guide into registering position with the center aperture, for automatically shutting off the supply of staples before the reciprocation of the staple plunger, and means operated by the movement of the rocking arm for causing the automatic operation of the staple and the plate feeding devices, substantially as described.

16. In a machine for inserting and clinching staples, the combination with the machine bed having a central aperture formed therein over which a plate rests on said bed, of a pivoted staple holding and feeding device, having a staple guide in connection therewith normally held above said aperture, but adapted to register with the same, a pivoted rocking arm having attached thereto a plunger adapted to reciprocate in said staple guide, a plate

holding device, a reciprocating plunger, actuated through intermediate mechanism by a lug on the rocking arm, adapted to successively feed each plate into position over the central aperture, a clinching mechanism situated in the central aperture, a hammer actuating the same pivoted to the machine bed, means for operating the rocking arm and thereby causing the pivotal movement of the staple holder, the reciprocation of the staple holder, the operation of the clinching mechanism and of the staple and plate feeding devices, and means, operating during the movement of the staple guide to register with the central aperture for automatically shutting off the supply of staples during the reciprocation of the staple plunger, substantially as described.

17. In a machine for inserting and clinching staples, the combination with a machine bed having a central aperture formed therein over which a plate rests on said bed, of a pivoted staple holding and feeding device having a staple guide in connection therewith, a pivoted rocking arm having attached thereto a plunger adapted to reciprocate in the staple guide, a plate holding and feeding device, a clinching mechanism situated in the central aperture, a hammer pivoted to the machine bed for actuating the same, and a bell crank lever for operating the rocking arm and thereby causing the pivotal movement of the staple holder, the reciprocation of the staple plunger, the actuation of the clinching hammer and the operation of the staple and plate feeding devices, substantially as described.

18. In a machine for inserting and clinching staples, a staple holding and feeding device, consisting of a trough for holding the staples, a removable staple carrier inserted therein, a spring actuated plunger fitting over the staple former for feeding the staples forward, and a staple guide block at the end of the trough provided with independent means for interrupting the forward feeding of the staples, substantially as described.

19. In a machine for inserting and clinching staples, a staple holding and feeding device, consisting of a trough for holding the staples, a removable staple carrier inserted therein, which is formed on its lower surface with inclined ends, and with a central longitudinal groove into which project lugs formed on the bottom of the trough, a spring actuated plunger fitting over the staple former for feeding the staples forward, and a staple guide block at the end of the trough provided with means for interrupting the forward feed of the staples, substantially as described.

20. In a machine for inserting and clinching staples, a staple holding and feeding device, consisting of a trough provided with a removable cover for holding the staples, a removable staple carrier inserted therein, a spring actuated plunger, provided with a locking device, for feeding the staples forward, and a staple guide block provided with means for

automatically interrupting the forward feed of the staples, substantially as described.

21. In a machine for inserting and clinching staples, a staple holding and feeding device, a staple guide block in connection therewith, gates sliding in the same for interrupting the forward feed of the staples, and means for operating said gates, substantially as described. 75

22. In a machine for inserting and clinching staples, a staple holding and feeding device, consisting of a trough for holding the staples, a removable staple carrier inserted therein, a spring actuated plunger for feeding the staples forward, a staple guide block, gates sliding in the same for interrupting the forward feed of the staples, and means for operating said gates, substantially as described. 80

23. In a machine for inserting and clinching staples, a staple holding and feeding device, consisting of a trough for holding the staples, a removable staple carrier inserted therein, a spring actuated plunger for feeding the staples forward, a staple guide block, gates 90 sliding in recessed ways cut in the inner face of the same for interrupting the forward feed of the staples, and means for operating said gates, substantially as described. 85

24. In a machine for inserting and clinching staples, a staple holding and feeding device, consisting of a trough for holding the staples, a removable staple carrier inserted therein, a spring actuated plunger for feeding the staples forward, a staple guide block, gates having inclined inner faces sliding in recessed ways cut in the inner face of the same, and means for operating said gates, substantially as described. 95

25. In a machine for inserting and clinching staples, a staple holding and feeding device, consisting of a trough for holding the staples, a removable staple carrier inserted therein, a spring actuated plunger for feeding the staples forward, a staple guide block having 110 gates sliding in the same for interrupting the forward feed of the staples, and levers, pivoted to the staple guide block, and provided with pins projecting through slots in the outer ends of the gates, for actuating the same, substantially as described. 105

26. In a machine for inserting and clinching staples, a staple holding and feeding device, consisting of a trough for holding the staples, a removable staple carrier inserted therein, a spring actuated plunger for feeding the staples forward, a staple guide block having 120 gates sliding in the same for interrupting the forward feed of the staples, levers, pivoted to the back of the staple guide, and provided with pins projecting through slots in the outer ends of the gates, for actuating the same, and a spring pressing on the levers for normally holding the same open, substantially as described. 125

27. In a machine for inserting and clinching staples,—the combination with a staple holding and feeding device having a staple guide in connection therewith, and provided with

means for interrupting the forward feed of the staples, of a staple inserting plunger adapted to reciprocate in said guide, a rocking arm for operating said plunger, means attached to said rocking arm for actuating the staple cut off mechanism, and means for operating said rocking arm, substantially as described.

28. In a machine for inserting and clinching staples, the combination with a staple holding and feeding device having a staple guide in connection therewith provided with means for interrupting the forward feed of the staples, of a plunger adapted to reciprocate in said guide, means brought into operation by said reciprocation for actuating the staple cut off mechanism, and means for reciprocating said plunger, substantially as described.

29. In a machine for inserting and clinching staples, the combination with the machine bed having a central aperture formed therein, of a staple holding and feeding device, pivoted to the machine bed, and having a staple guide in connection therewith normally held above the central aperture but adapted to register with the same, and provided with means for interrupting the forward feed of staples, a staple inserting plunger adapted to reciprocate in said staple guide, means for interrupting the forward feed of staples during the pivotal movement of the staple guide and before the reciprocation of the plunger, and means for reciprocating said plunger, substantially as described.

30. In a machine for inserting and clinching staples, the combination with the machine bed having a central aperture therein, of a staple holding and feeding device, pivoted to the machine bed, and having a staple guide in connection therewith, which is adapted to register with the central aperture, and provided with means for interrupting the forward feed of the staples, a pivoted rocking arm having a plunger attached thereto which is adapted to reciprocate in the staple guide, means on said rocking arm for actuating the staple cut off mechanism during the pivotal movement of the staple guide, and before the reciprocation of the plunger, and means for operating said rocking arm, substantially as described.

31. In a machine for inserting and clinching staples, the combination with the machine bed having a central aperture therein, of a staple holding and feeding device, pivoted to the machine bed, having a staple guide in connection therewith adapted to register with the aperture in the machine bed, and provided with sliding gates, operated by levers pivoted to the staple guide, for cutting off the forward feed of the staples, a rocking arm pivoted to the machine bed, a staple inserting plunger attached to the rocking arm and adapted to reciprocate in the staple guide, means for actuating the rocking arm, and pointed plates attached to the rocking arm and adapted to actuate the staple cut off mechanism during

the pivotal movement of the staple guide, and before the reciprocation of the plunger, substantially as described.

32. In a machine for inserting and clinching staples, the combination with the machine bed having a central aperture therein, of a staple holding and feeding device, pivoted to the machine bed, having a staple guide in connection therewith adapted to register with the aperture in the machine bed, and provided with means for cutting off the forward feed of the staples, a rocking arm pivoted to the machine bed, a staple inserting plunger provided with a longitudinal slot attached to the rocking arm by a link connection and to the staple guide block by a pin running longitudinally through it, and adapted to reciprocate in said staple guide, means attached to the rocking arm for cutting off the supply of staples during the pivotal movement of the staple guide block, and before the reciprocation of the plunger, and means for operating said rocking arm, substantially as described.

33. In a machine for inserting and clinching staples, the combination with the machine bed having a central aperture therein, of a staple holding and feeding device pivoted to the machine bed, having a staple guide in connection therewith adapted to register with the opening in the machine bed, a rocking arm pivoted to the machine bed and normally held backward by a spring, a staple inserting plunger attached to said rocking arm, and also to the staple guide, a spring for maintaining a normally constant distance between the staple guide and the rocking arm, means attached to the rocking arm for actuating the staple cut off mechanism before the reciprocation of the staple plunger, and means for operating the rocking arm, substantially as described.

34. In a machine for inserting and clinching staples, the combination with a machine bed having a central aperture formed therein, and a rocking arm pivoted to said bed, and having a staple feeding and clinching mechanism connected thereto of a plate holding device, means for controlling the upward feed of the plates, a reciprocating plunger for successively placing the plates in position over the central aperture, means operating by the movement of the rocking arm for reciprocating said plunger, and means for operating said rocking arm, substantially as described.

35. In a machine for inserting and clinching staples, the combination with a machine bed having a central aperture formed therein, and a rocking arm, pivoted to said bed and having a projecting lug formed on one side of the same, of a plate holding and feeding device, means for controlling the upward feed of the plates, a reciprocating plunger for successively placing the plates in position over the central aperture, a lever pivoted to the machine bed, attached to said plunger by a connecting rod, and adapted to be actuated

by the lug on the rocking arm for reciprocating said plunger, and means for operating said rocking arm, substantially as described.

36. In a machine for inserting and clinching staples, the combination with a machine bed having a central aperture formed therein, and a rocking arm pivoted to said bed and having a lug formed on one side of the same, of a plate holding device, the bed plate 6, having the longitudinal slot 63 formed therein, over which the plate 64 is placed, for limiting the upward feed of the plates, a reciprocating plunger for successively placing the plates in position over the central aperture, a lever pivoted to the machine bed, attached to said plunger by a connecting rod, and adapted to be actuated by the lug on the rocking shaft, for operating said plunger, and means for operating said rocking arm, substantially as described.

37. In a machine for inserting and clinching staples, the combination with a machine bed having a central aperture formed therein, of the two clinching blades 70, formed with slots and suspended upon pins passing through said

slots in said central aperture with their upper ends normally apart, and means for forcing the said upper ends together, and then forcing upward the entire clinching blades, substantially as described.

38. In a machine for inserting and clinching staples, the combination with a machine bed having a central aperture formed therein, of the two clinching blades 70, hanging upon supporting pins in said aperture with their upper ends normally apart, a hammer pivoted to the machine bed and provided with an aperture in its front end through which the lower ends of the clinching blades pass, a V-shaped lug, formed in said aperture and entering between the said lower ends, and means for operating the hammer, substantially as described.

In testimony whereof we affix our signatures in presence of two witnesses.
